CLAIM

The ornamental design for a portable lighted wireless qi charging makeup case, as shown and described.

DESCRIPTION

FIG. 1 is a front perspective view of the portable lighted qi charging makeup case shown in an opened position;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a front perspective view of an embodiment of the portable lighted qi charging makeup case shown in an opened position; and,

FIG. 9 is a front perspective view of the portable lighted qi charging makeup case shown in a closed position.

The broken lines show portions of the article not claimed and forms no part of the claimed design.

1 Claim, 6 Drawing Sheets
